Walter Jenkins

UNITED STATES PATENT OFFICE.

WALTER JENKINS, OF JOLIET, ILLINOIS.

IMPROVEMENT IN DIES FOR FORMING FENCE-BARBS.

Specification forming part of Letters Patent No. 222,976, dated December 23, 1879; application filed June 25, 1879.

To all whom it may concern:

Be it known that I, WALTER JENKINS, of the city of Joliet, county of Will, and State of Illinois, have invented a new and useful Improvement in Combined Punch and Die for the purpose of making sheet-metal four-pointed tongued barbs for barbed-wire fences; and I do hereby declare that the following is a full, clear, and exact description of the construction and operation of the same, reference being had to the accompanying drawings, making a part of this specification, in which—

Figure 1 is a side view of the punches arranged and socketed in a base, as designed for use, F being the diamond-shaped punch, and G the wedge-shaped punch, with its right-angled notch *h*, at its outer upper edge, forming a small punch, *b*, and having a downward inward bevel, *c*. The punches are held in place by set-screws *x y*. The punch G is slightly higher than the punch F, and is used to form the tongue of the barb and to assist in forming two of the projecting points.

Fig. 2 is a view of the punches F G, looking vertically down upon them.

Fig. 3 is a top view of the die K as arranged for use, showing the Y-shaped opening, this Y-shaped opening being of suitable and corresponding shape and size to easily receive the punches in forming the barb. The stem of the Y receives the wedge-shaped punch G, with the inward bevel and right-angle notch, and the mouth or receding arms of the Y receives the inner half of the diamond-shaped punch F. This die is constructed in two equal parts, as indicated by the line *e*, and is connected together by any suitable pin, (not shown in the drawings,) the object being that the die may be taken apart and sharpened or repaired. The Y-shaped opening is narrowest, and the lines or edges thereof most perfectly formed at the upper surface of the die K, to form a close fit with the punches and insure a perfect cutting of the barb and its tongue; and the walls of the opening recede from each other as they descend, so as to enlarge the space below the surface of the die, to permit the tongue of the barb, which is bent down into this space in

forming, to be easily withdrawn without coming in contact with the side walls of the opening.

Fig. 4 represents a plan view of the barb as formed or produced by the punches and die, showing four sharp projecting points.

Fig. 5 represents a side view of the same barb, showing the curved tongue *f* as produced by the punch G, and arranged for easily clasping the wire.

Like parts are indicated by the same letters in the drawings.

The points of the punches F and G are placed and held far enough apart to leave intact sufficient metal between them to form the body of the barb, and the die and punches are set in any suitable machine to operate them, so that the half of the diamond-shaped punch, adjacent to the other punch, shall fall between the upper arms of the Y-shaped opening of the die, and the punch G shall fall into the lower portion or stem of the Y. The die is made stationary, and the punches play up and down together, being elevated above its upper surface sufficient to allow the metal of which the barb is formed to pass between, and pressed down sufficiently below to cut the barb and form the tongue. A strip of metal of the requisite thickness and of the desired width of the barb is passed lengthwise between the punches and die in forming the barb, and is first cut pointed at the end by the diamond-shaped punch and arms of the Y, and on the next ascent of the punches the strip is moved forward until the end of the point previously cut comes flush with the lower end of the stem of the Y, when the punches come down upon it, the highest point of the bevel *c* striking first, and cutting and bending the tongue of the barb, the small outer portion, *b*, of the punch following and cutting open the rest of the center at the pointed end of the strip, thereby forming the two sharp points of the barb at the forward end of the strip, and the diamond-shaped punch cutting the rear opening, which embraces the entire width of the strip and corresponds to the arms of the Y, and, again, at the same time pointing the end of the strip from which the barb was cut for

another operation, each descent of the punches after the first forming a complete barb, as shown in Figs. 4 and 5.

By the above-described means a four-pointed flat metal-tongued barb is formed, which can be easily attached to a fence-wire by any suitable machinery.

Having thus described my invention, what I claim as new, and desire to secure by Letters Patent, is—

The reversible diamond-shaped punch F, in combination with the punch G, having the elevated bevel-point c, and the die K, having the Y-shaped opening, all arranged and operating substantially as and for the purpose specified.

WALTER JENKINS.
